Maurice Block

UNITED STATES PATENT OFFICE.

JACOB KALMANOWITZ, OF BROOKLYN, NEW YORK.

WASHING-MACHINE.

1,376,815.

Specification of Letters Patent.

Patented May 3, 1921.

Application filed March 1, 1921. Serial No. 448,755.

To all whom it may concern:

Be it known that I, JACOB KALMANOWITZ, a resident of Brooklyn, Kings county, State of New York, and a citizen of the United States of America, have invented certain new and useful Improvements in Washing-Machines, of which the following is a specification.

This invention relates to improvements in washing machines, one of the objects being to provide a portable device arranged to wash clothes by means of especially arranged paddles or paddles located within a corrugated vessel, suitable means being provided to maintain the water within the vessel heated to the desired extent.

One of the features of my invention is a novel form of paddle carrier designed to have imparted thereto movement longitudinally of the vessel during the rotation of the carrier, whereby the clothes will have imparted thereto, by paddles carried by the carrier, a double movement which will tend to bring them in better contact with the water, that is to say, into better cleansing contact.

I will now proceed to describe my invention in detail, the novel features of which I will point out in the appended claims, reference being had to the accompanying drawing wherein:—

Figure 1 is a longitudinal sectional view of my improvement;

Fig. 2 is a vertical sectional view, the section being taken on a line 2—2 in Fig. 1;

Fig. 3 is a fragmentary sectional view, illustrating the mechanism to impart to the paddle carrier movement longitudinally of its receptacle; and

Fig. 4 is a sectional detail view of the paddle carrier and paddles, the section being taken on line 4—4 in Fig. 1.

My improved washing machine is made up of a corrugated cylindrical vessel or receptacle 5 having a removable top 6 to cover an opening 7 through which clothes to be washed will be passed. Within the vessel I mount a paddle carrier 8 upon a shaft 9 which projects beyond one end of the receptacle 5 to receive a handle 10. The shaft at one end is journaled in a bearing 11 carried by the head 12 of the receptacle 5. The opposite head 13 of the receptacle carries a stuffing box 14 through which shaft 9 passes. The stuffing box 14 prevents leakage of water or steam.

The paddle carrier 8 is loosely mounted upon shaft 9 and can be moved longitudinally thereof. The shaft 9 and carrier 8 are rotatably connected to a feather 15 carried by shaft 9 which slidably engages a keyway 16 in carrier 8 (see Fig. 3). The carrier is arranged to slide upon feather 15 longitudinally of shaft 9. One end of carrier 8 carries an arm 17 provided with a roller 18 to travel along the sinuous face 19 of a cam-block 20, carried by head 13 and arranged concentric to the peripheral surface of shaft 9. Between the opposite end of carrier 8 and head 12, I locate a spiral compression spring 21 which acts to maintain roller 18 in contact with face 19 of block 20. The carrier 8 is provided with paddles 22 by which the clothes are stirred or caused to be passed through the water in receptacle 5.

After water has been placed in receptacle 5 and clothes put in the water, handle 10 will be turned causing shaft 9 and paddles 22 to rotate, thereby causing the clothes to be carried around in contact with the corrugations 23 which will act as a wash board to cleanse the clothes. During the rotation of shaft 9, carrier 8 will have imparted thereto a reciprocating movement due to the cam-block 20, as the face 19 thereof will cause the carrier to move longitudinally of the shaft 9. While face 19 will move the carrier in one direction, spring 21 will move the carrier in the opposite direction; hence, the reciprocating movement referred to. This movement in combination with the rotary movement will thoroughly agitate the clothes and water, whereby a desired cleansing action will result. To maintain the water heated during a washing operation, I employ a burner 24 having gas jets 25. Numeral 26 indicates a valve to draw off water from the receptacle 5.

Having described my invention, what I claim and desire to secure by Letters Patent is:—

1. In a washing machine, a receptacle for clothes, a carrier fixedly secured thereto within same, paddles carried by the carrier, means to rotate the carrier, and means to impart to said carrier a reciprocating movement longitudinally of the receptacle during the rotation thereof.

2. In a washing machine, a corrugated cylindrical receptacle for clothes, paddles carried by the carrier, extending longitudi-

nally of the carrier, means to rotate the carrier, and means to impart to said carrier a reciprocating movement longitudinally of the receptacle during the rotation thereof.

5. 3. In a washing machine, a receptacle for clothes, a carrier within same, paddles carried by the carrier, means to rotate the carrier, a cam within the receptacle to move the carrier in one direction longitudinally of the 10 receptacle, and a spring to move the carrier longitudinally of the vessel in the opposite direction.

4. In a washing machine, a receptacle for clothes, a shaft extending longitudinally thereof, a carrier carried by the shaft movable longitudinally thereof, paddles carried by the carrier, a block surrounding the shaft having a sinuous face, a roller carried by the carrier bearing against said sinuous face, 15 a spring to maintain said roller in contact with said sinuous face, and means to rotate the carrier.

5. In a washing machine, a receptacle for clothes, a rotatable shaft extending longitudinally thereof and projecting from one end of said receptacle, a handle carried by the projecting end of the shaft, a carrier within the receptacle mounted on said shaft but 20 slideable longitudinally thereof, means 25 to rotatably connect the shaft and carrier, 30 paddles carried by the carrier, a block sur-

rounding the shaft having a sinuous face, a roller carried by the carrier bearing against said sinuous face, a spring to maintain said roller in contact with said sinuous face, and 35 means to rotate the carrier.

6. In a washing machine, a receptacle for clothes, a rotatable shaft extending longitudinally thereof, means to rotate the shaft, a carrier slidably mounted on said shaft and rotatable therewith, an arm carried by the carrier extending outwardly from one end thereof in parallelism with the axis of the carrier, a roller carried by the arm at its outer end, a block surrounding the shaft having a sinuous face, a spring bearing against the carrier to maintain the roller in contact with the sinuous face of the block, and paddles carried by the carrier extending longitudinally thereof. 40 45 50

7. In a washing machine, a receptacle for clothes, a rotatable shaft extending longitudinally thereof, a carrier movable longitudinally of the shaft but rotatable therewith, paddles carried by the carrier, and means to operate the carrier and paddles 55 longitudinally of the receptacle in a fixed plane when said shaft is rotated, said paddles being fixedly secured to the carrier.

In testimony whereof I hereunto affix my 60 signature.

JACOB KALMANOWITZ.
